UNITED STATES PATENT OFFICE.

CONRAD MEYER, OF NEW YORK, N. Y.

EYEGLASS-MOUNT.

1,266,513.

Specification of Letters Patent. Patented May 14, 1918.

Application filed June 5, 1917. Serial No. 172,894.

To all whom it may concern:

Be it known that I, CONRAD MEYER, a citizen of the United States, and a resident of the city of New York, borough of Manhattan, in the county and State of New York, have invented a new and Improved Eye-glass-Mount, of which the following is a full, clear, and exact description.

This invention relates to eye glass mounts and has for an object the provision of an improved construction for supporting the lens through the action of interlocking members.

Another object of the invention is to provide a post and guard with connecting means fitting in a plurality of slots arranged at angles to each other.

A further object of the invention is to provide an improved mount which will necessitate slots in the lens and clamping members fitting into the slots interlocking with the guard.

In the accompanying drawing:—

Figure 1 is a front elevation of a lens and mount disclosing the invention.

Fig. 2 is a fragmentary side elevation of one end of the lens shown in Fig. 1, the same disclosing the arrangement of slots.

Fig. 3 is a view similar to Fig. 2 but showing the fastening means applied.

Fig. 4 is a longitudinal vertical section through the mount and associated parts shown in Fig. 1, the same being on an enlarged scale.

Fig. 5 is an edge view of the mount shown in Fig. 4.

Fig. 6 is a perspective view of the blank of one of the fastening means.

Fig. 7 is a perspective view of one of the fastening means ready to be inserted.

Referring to the accompanying drawing by numerals, 1 indicates a lens of any desired kind and 2 a post forming part of the mount, said post being preferably formed integral with the guard 3 extending on each side of post 2 and provided with a number of depending protecting covering arms 4, there being four arms as shown in the drawing for covering the slots 5 and 6 and the members arranged in said slots. These arms in addition to covering the slots and associated parts act to prevent any side movement of the mount and are preferably formed so as to pinch or slightly press against the lens 1, though this is not abso-

lutely necessary. In addition to the arms 4 covering the slots 5 and 6 the guard 3 is provided with overhanging flanges 17 and 18 which assist in preventing lateral or side movement of the guard and cover the section 8 of the securing means as well as the elastic 14. As shown in Fig. 2, the lens 1 is provided with the slots 5 and 6 which are converging, as the same is the preferable arrangement, though diverging slots may be used if preferred and any desired angle of convergence or divergence may be substituted for that shown without departing from the spirit of the invention.

A securing or locking member 7 is provided for each of the slots 5 and 6, said securing or locking members being formed first as shown in Fig. 6 and then as shown in Fig. 7, in which formation they are ready to be applied as shown in Fig. 3. It will be noted that the locking member 7 is provided with a body 8 designed to engage flatwise the edge of the lens 1, with an upstanding locking extension 9 and a depending member 10 having a turned-up section 11. The section 11 is preferably pressed against the depending member 10 when in position, though the resiliency of the metal will cause the section 11 to exert a slight continuous strain against the lens and thereby prevent any loose motion. In the drawing a space has been shown between the extension 11 and the depending portion 10, but this is merely for the purpose of illustration, as these members are in contact or substantially in contact when in use. The arrangement of the securing or locking member 7 with the turned-over section 11 is desirable but is not absolutely necessary, as the slots 5 and 6 could be made of such a width as to accommodate the extension 10 of member 7 so that the extension snugly fits therein. If preferred the extension or depending member 10 could be made somewhat thicker than the remaining part of the securing member 7 so as to snugly fit the slots 5 and 6.

After the locking members 7 are arranged as shown in Fig. 3 the guard 3 may be slipped thereover, said guard having openings 12 and 13, as shown in Fig. 5, through which the locking extension 9 of each member 7 projects. Before placing the guard 3 and post 2 in position a rubber or other elastic member 14 is arranged in the guard 3 and may be of such a length as to substan-

tially fill the space between the members 12 and 13 so that when the guard is pressed slightly against the edge of the lens the ends of the extension 9 may be bent over as shown in Fig. 4, where there will be a slight tension against the edge of the glass and against the edge of the slots 5 and 6.

In order to produce a better appearing article the ends 15 and 16 are turned over as shown in Fig. 4 so as to contact or substantially contact with the edge of the lens 1. By providing the slots 5 and 6 and the fastening means as described the post 2 is firmly held in position without the use of screws, cement or other extra clamping or attaching means. It will be noted that all of the parts which act against the lens act against the edge of some part of the lens, either against the outer periphery or against the edge of one of the slots, so that an extra strong pressure may be exerted without in any way injuring the lens, which would be the case if a screw was used which passed transversely through the lens. It will also be noted that the slots 5 and 6 and the parts covering the same extend only a very short distance into the lens, as shown in Fig. 1, whereby practically all of the lens is used and, consequently, a smaller lens may be caused to do the work of what otherwise would require a larger lens where a considerable portion of the lens is occupied by the retaining screws or other clamping means.

What I claim is:

36 1. In an eye glass mount of the character described, the combination with a lens having a pair of slots therein extending to the edge, of a guard provided with a flange extending its full length overlapping said lens 40 and with end sections overlapping said slots, said guard having a post and an aperture adjacent each side of said post, and fastening means for clamping said guard to said lens, said fastening means comprising a 45 pair of metallic strips having one end fitting into said slots and the opposite end extending through said apertures, said opposite ends being positioned against the outer surface of said guard.

50 2. In an eye glass mount of the character described, a guard provided with a post, means extending into a lens, and formed with resilient ends gripping part of said lens, said means acting on said guard for 55 pressing the guard against the edge of the lens and a rubber member arranged between said guard beneath said post and said lens.

3. An eye glass mount, comprising a guard, and a plurality of fastening means 60 having one end extending through and overlapping the guard and the opposite end interlocking with a lens.

4. In a device of the character described, the combination with a lens having a plurality of slots arranged at an angle to each

other, of a guard, and fastening means extending through the guard and snugly fitting said slots.

5. In a device of the character described, the combination with a lens having slots extending from the periphery, of a guard, and means snugly fitting in said slots and extending through said guard for clamping the guard to the lens.

6. In a device of the character described, the combination with a lens having slots arranged therein extending from the periphery, of a guard, and means fitting in said slots and extending through said guard formed so as to draw the guard and the lens together.

7. In an eye glass mount of the character described, the combination with a lens having converging slots extending from the periphery, of a guard shaped so as to conform substantially to the periphery of said lens and of such a length as to overlap both of said slots, and means arranged in said slots formed with extensions projecting through said guard and interlocking therewith for securing the guard and the lens together.

8. In an eye glass mount of the character described, the combination with a lens having converging slots, of a guard having openings, metallic members snugly fitting said slots and extending through said openings, said metallic members having the ends bent over so as to engage the upper surface of the guard for connecting the guard with the lens.

9. In an eye glass mount of the character described, the combination with an eye glass having a pair of spaced converging slots, a guard of sufficient length to extend slightly beyond each of said slots, a rubber member arranged in said guard and adapted to engage the edge of said lens, and a securing member formed with ends bent upon themselves fitting in each of said slots for gripping the lens, said securing means interlocking with said guard in such a manner as to slightly press said resilient means whereby the guard is connected with the lens and is maintained continually under tension.

10. In an eye glass mount of the character described, the combination with a lens having spaced converging slots, of a guard conforming to the shape of the edge of the eye glass spanning said slots, said guard having a pair of apertures therein, and metallic members arranged in each of said slots and snugly fitting the same, said metallic members being formed with a body engaging part of the periphery of the lens and an extension extending through said slots, said extensions being bent over and resting against the outer face of said guard.

11. In an eye glass mount of the character described, the combination with a lens hav-

ing converging slots extending from the periphery, of a guard conforming to the shape of the periphery and extending from one slot to the other, said guard being provided with a pair of arms adjacent each end overlapping said slots and covering the same, and a connecting member snugly fitting into each of said slots and extending through the guard overlapping the guard and thereby connecting the guard with the lens.

12. In an eye glass mount of the character described, the combination with a lens having converging slots, of a guard provided with a post and with a pair of arms at each end, said arms overlapping said slots for covering the same, said guard having an opening adjacent each side of said post, and a metallic member arranged in each of said slots and snugly fitting the same, said metallic members having extensions projecting through said openings and interlocking with the guard for clamping the guard and lens together.

13. In an eye glass mount of the character described, the combination with a lens having converging slots, of a guard having a pair of openings and a metallic member formed with a bent-back section, said bent-back section of each of said metallic members being fitted into said slots and pressing against the walls thereof, the opposite end of said metallic members projecting through and interlocking with said guard for connecting the same with said lens.

14. In an eye glass mount of the character described, the combination with a lens having converging slots, a guard extending from one slot to the other, said guard having openings spaced appreciable distances from the respective slots, a connecting member for each of said slots, each of said connecting members comprising a projection extending through said opening in said

guard, and a looped or bent-back portion snugly fitting and pressing against the walls of said slots.

15. In an eye glass mount of the character described, the combination with a lens having slots extending from the periphery at different angles, of a guard having a pair of openings spaced from said slots, a resilient member arranged between said openings, and metallic connecting members fitting in said slots and extending parallel with the periphery of the lens from the respective slots to said openings and then through the openings and along the outer surface of the guard.

16. In an eye glass mount of the character described, a lens having slots extending from the periphery at different angles, a guard having openings spaced from said slots, a resilient member arranged between said openings, and a metallic connecting member for each of said slots, each of said connecting members having a looped end substantially filling the slot in which it is arranged and pressing against the walls thereof, each of said connecting members having a body extending parallel with and along the periphery of the lens to one of said openings, through said opening and in contact with the other surface of the guard, said connecting members being so positioned as to maintain said resilient member under compression.

17. In an eye glass mount of the character described, the combination with a lens having diverging slots, of securing members snugly fitting said slots, said securing members having extensions, a guard fitting over said securing members and said slots, said guard being provided with arms covering said slots and an overhanging flange on each side for preventing lateral motion, said guard being also provided with apertures for accommodating said extensions.

CONRAD MEYER.
